S. MENDOZA

COMBINED STREET CURBING STRUCTURE AND ADVERTISING MEANS

Filed March 10, 1927

Patented Nov. 8, 1927.

1,648,459

UNITED STATES PATENT OFFICE.

SALVADOR MENDOZA, OF LOS ANGELES, CALIFORNIA.

COMBINED STREET-CURBING STRUCTURE AND ADVERTISING MEANS.

Application filed March 10, 1927. Serial No. 174,344.

My invention relates to a combined structure for forming the curbing of streets and for providing means in connection therewith for advertising purposes.

- 5 The objects of my invention are: first, to provide a structure of this class which will form a rigid, strong, and neat curbing between sidewalks and streets; second, to provide a structure of this class which will provide an efficient form and permanent retaining means for the edge of the sidewalk; third, to provide a structure of this class which will serve as a rigid curbing, as well as an advertising means at its outer side; 10 fourth, to provide advertising means in connection with curbing structures which are advantageously located with respect to the sidewalks and streets, which are protected, which are efficiently enclosed, and which are 15 readily accessible; fifth, to provide means, in connection with a structural steel element adapted for supporting concrete construction, which serves as an illuminating means, guiding means, advertising means, or the 20 like, in the side of the structural steel element; sixth, to provide a curbing structure which provides the outer edge of and a form for constructing a sidewalk, which structure comprises a plurality of long structural steel 25 elements, abutted and secured together at their ends, which elements are adapted to be wholly enclosed, except at their front sides and at the extreme outer portion of their upper faces, by the material of which the 30 sidewalk is constructed; seventh, to provide a continuous structural steel curbing structure having sectional transparent plates over a continuous channel at its outer side and sectional retaining means for said plates, 35 whereby said plates may be readily removable for repair, substitution, changing of advertising, repairing of illuminating means in the channel, and the like; eighth, to provide a novel shape for a structural steel element 40 of the class mentioned; ninth, to provide novel advertising means, or the like, in connection with a curbing structure; tenth, to provide a structure of this class in combination with concrete or similar construction 45 which is adapted for displaying in illuminated form at the outer side thereof advertising, street names, house and building numbers, and building names, and eleventh, to provide a structure of this class which is 50 simple and economical of construction proportionate to its functions and which will

not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Fig. 1 is a fragmentary perspective view of a street corner showing a corner building, a sidewalk adjacent thereto, and my new curbing structure constructed at the outer edges and the rounded corner of the sidewalk; Fig. 2 is an enlarged fragmentary sectional view thereof, taken at 2-2 of Fig. 1, showing particularly my curbing structure; Fig. 3 is an enlarged fragmentary side elevational view thereof, showing the same contracted in length for the purpose of illustration; Fig. 4 is a fragmentary plan view thereof taken at 4-4 of Fig. 3, showing the means of connecting two of the structural elements together; and, Fig. 5 is a fragmentary sectional view taken through 5-5 of Fig. 3, showing means of connecting the ends of the sectional transparent plates. 75 80 85

Like characters of reference refer to similar parts and portions throughout the several views of the drawings.

The essential element of my structure is designated 1 in the drawings and is adapted, 90 in its preferred form, to form the edge of the sidewalk, designated A, at its one side, and for enclosing an illuminating and advertising means at its outer side. This element 1 is substantially I-shaped in cross section, having a channel 1^a at its normally inner side and a channel 1^b at its normally outer side, the latter being preferably of considerably greater depth than the former, as shown in Fig. 2. The upper flange of the element 1 is provided with a longitudinal depression 1^c which is spaced inwardly from the front side of the element and the bottom of which is positioned below the upper face of the outer portion of the upper flange. 95 100 105 The portion at the outer side of the element 1 which extends above the bottom of the depression 1^c, and designated 1^d, serves as a forming edge for the sidewalk and means for retaining the concrete. Said depression 110 is essentially provided for receiving a concrete cap homogeneous with the sidewalk so

that only a narrow metal ledge is provided at the edge of the sidewalk. The element 1 is so shaped as to be continuously made and rolled, in rolling mills, from structural steel. 5 The elements 1 are made of considerable length, such as rail lengths, for economy of construction. When laid in position at the curbing, the same are secured together at their abutting ends by means of plates 2 and screws 3, which plates are positioned in the depressions 1^e and covered by the concrete cap of the sidewalk, as shown. 10 The element 1 may be shaped or curved into any form desired to suit conditions, such as the curved corner element, designated 15 in Fig. 1. Near the outer edges of the lower side of the upper flange and the upper side of the lower flange, are respectively provided longitudinal grooves 1^e and 1^f into which are positioned the upper and lower edges of the transparent plate 5, which is preferably a glass plate. To protect the edges of the glass plate, and also to seal the compartment formed by the channel 1^b, I have provided at the upper and lower edges of said plate, U-shaped yieldable members 6 which are preferably made of rubber, or other similar suitable material. The upper edge of 20 the glass plate is retained in position by a metal bar 7 which is secured in position by screws 8, the bar or strip 7 forming the outer side of the groove 1^e. It will be noted that, if desired, the groove 1^e may be formed 25 with the element 1 without employing the retaining bar 7. The bars 7 are preferably made of considerable length and may form, for all practical purposes, an integral part of the element. The lower edge of the glass plate 5 is retained in position by a retaining member or strip 9 which is preferably at its 30 lower edge, by means of pins 10, to lugs 1^g of the element 1 and positioned below and outside of the groove 1^f but inwardly from the outer face of the element 1, as shown in 35 Figs. 2 and 3. Although the retaining members 9 are pivoted, as described, the same, when shifted upwardly over the lower edge of the glass plate 5, are secured in position 40 by screws 11. It will be here noted that for convenience of construction, operation and repair, the plate 5, as well as the retaining strip 9, are made in lengths convenient for handling, as shown in Figs. 1 and 3. Between the ends of the glass plates 5, are positioned gaskets 12, or other suitable means, for sealing the abutting joints of said plates, as shown in Fig. 5. Within the channel 1^b 45 of each element 1 are positioned a plurality of electric sockets 13 which may be secured to the upper side of the lower flange of the element 1 by means of screws 14. These sockets are spaced so as to provide uniform distribution of light by the electric bulbs 50 mounted in said sockets. The channel 1^a

also serves as the conduit for the wires 16 to which the sockets are connected.

The structure, as shown, may be used as an illuminating means for the street, or for indicating the names of streets, and numbers 70 and names of buildings, or the same may be used for advertising purposes. The names, numbers, and advertising matter may be painted or otherwise provided on the inner side of the plates 5, as indicated by 17 in 75 Fig. 2.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims. 80

Having thus described my invention, what I claim as new and desire to secure by Letters Patent is:

1. In a street curbing structure, a metal bar comprising a web and flanges at its upper and lower edges forming a channel at the outer side of the bar, a transparent plate positioned over the outer portion of said channel, means at the adjacent sides of the edges of said flanges for securing said plate in position, and illuminating means positioned in said channel behind said plate. 90

2. In a street curbing structure, a metal bar comprising a web and flanges at its upper and lower edges forming a channel at the outer side of the bar, the upper side of the upper flange having a depression spaced 100 backwardly from the front edge of the upper flange, the bottom of the depression being positioned below the upper face of the front portion of said flange. 105

3. In a street curbing structure, a metal bar comprising a web and flanges at its upper and lower edges forming a channel at the outer side of the bar, the adjacent inner sides of said flanges being provided near their outer edges with grooves, a transparent plate positioned with its upper and lower edges in said grooves, and means for retaining said plate in said grooves from the outer 110 side of the structure. 115

4. In a street curbing structure, a long structural form metal member having a wide and deep longitudinal channel at its normally outer side, a transparent plate positioned over the outer portion of said channel, means at the opposite sides of said channel and adjacent the normally outer side of said member for securing said plate in position from the outer side of the structure, an illuminating means positioned in said channel behind said plate. 120

5. In a street curbing structure, a long metal member having a wide and deep longitudinal channel at its normally outer side 130

and plate positioning grooves at the opposite sides of said channel adjacent the normally outer side of said member, a transparent plate positioned with its upper and lower edges in said grooves from the outer side of the structure and means for retaining said plate in said grooves.

6. In a street curbing structure, a long metal bar comprising a web and flanges at its upper and lower edges forming a channel at the outer side of the bar, the adjacent inner sides of said flanges being provided near their outer edges with grooves, a transparent plate positioned with its upper and lower edges in said grooves, a metal strip secured over the outer side of the upper groove for retaining the upper edge of said plate, and a metal retaining strip pivotally mounted on the lower flange outside of the lower groove, and screw means securing said metal retaining strip against the lower edge of said plate.

7. In a street curbing structure, a long metal bar comprising a web and flanges at its upper and lower edges forming a channel at the outer side of the bar, the adjacent inner sides of said flanges being provided near their outer edges with grooves, a transparent plate positioned with its upper and lower edges in said grooves, a metal strip secured over the outer side of the upper groove for retaining the upper edge of said plate, a metal retaining strip pivotally mounted on the lower flange outside of the lower groove, screw means securing said metal retaining strip against the lower edge of said plate, and yieldable U-shaped strips positioned over the opposite edges of said plate for protecting said plate and for making the compartment behind the same waterproof.

8. In a street curbing structure, a substantially I-shaped steel bar forming channels at its opposite sides, the normally inner channel forming means for receiving concrete for supporting a sidewalk, a transparent plate positioned over the outer portion of the normally outer channel, and means for retaining said transparent plate in position over the last mentioned channel and to the upper and lower flanges of said bar.

9. In a street curbing structure, a plurality of metal bars, each comprising a web and flanges at its upper and lower edges forming a channel at the outer side of the bar, said bars having depressions in the upper sides of the upper flanges, plates positioned in said depressions for securing the adjacent ends of said bars together, sectional transparent plates positioned over the outer portions of the channels in each bar, means at the adjacent sides of the edges of said flanges for securing said sectional plates in position, and illuminating means positioned in said channels behind said sectional plates.

10. In a street curbing structure, a plu-

rality of metal bars, each comprising a web and flanges at its upper and lower edges forming a channel at the outer side of the bar, said bars having depressions in the upper sides of the upper flanges, plates positioned in said depressions for securing the adjacent ends of said bars together, sectional transparent plates positioned over the outer portions of the channels in each bar, means at the adjacent sides of the edges of said flanges for securing said sectional plates in position, illuminating means positioned in said channels behind said sectional plates, and yieldable means positioned over the upper and lower edges of said plates and between the adjacent ends thereof for protecting said plates and for forming a waterproof compartment behind the same.

11. In a street curbing structure, a plurality of substantially I-shaped metal bars abutted end to end, the channels at the normally inner sides thereof being adapted for receiving concrete and for supporting sidewalks, the upper sides of the upper flanges having longitudinal depressions spaced backwardly from the front sides of the bars and with the bottoms thereof below the upper faces of the outer portions of the upper flanges, plates positioned in said depressions for connecting the adjacent ends of said abutting bars, said plates being also positioned below the upper faces of the outer portions of the upper flanges, said depressions being adapted for receiving concrete for forming the upper face of the sidewalk, and illuminating means in the outer channels of said bars.

12. In a street curbing structure, a plurality of substantially I-shaped metal bars abutted end to end, the channels at the normally inner sides thereof being adapted for receiving concrete and for supporting sidewalks, the upper sides of the upper flanges having longitudinal depressions spaced backwardly from the front sides of the bars and with the bottoms thereof below the upper faces of the outer portions of the upper flanges, plates positioned in said depressions for connecting the adjacent ends of said abutting bars, said plates being also positioned below the upper faces of the outer portions of the upper flanges, said depressions being adapted for receiving concrete for forming the upper face of the sidewalk, sectional transparent plates positioned at the outer portions of the normally outer channels forming enclosed compartments behind the same, means for retaining said sectional plates in position to the upper and lower flanges of said bars, and illuminating means positioned in said channels behind said plates.

13. In a structure of the class described, the combination with concrete construction, of a metal bar imbedded in the side of the

concrete construction, said bar comprising a web and flanges at its upper and lower edges forming a channel at the outer side of the bar, a transparent plate positioned over the outer portion of said channel, and means at the adjacent sides of the edges of said flanges for retaining said plate in position.

14. In a structure of the class described, the combination with concrete construction, 10 of a metal bar imbedded in the side of the concrete construction, said bar comprising a

web and flanges at its upper and lower edges forming a channel at the outer side of the bar, a transparent plate positioned over the outer portion of said channel, and illuminating means positioned in said channel behind said plate.

In testimony whereof, I have hereunto set my hand at Los Angeles, California, this 28th day of February, 1927.

SALVADOR MENDOZA.
